UNITED STATES PATENT OFFICE.

GEORGE H. SARGENT, OF CHICAGO, ILLINOIS.

CAR-REPLACER.

No. 909,944.

Specification of Letters Patent.

Patented Jan. 19, 1909.

Application filed June 12, 1908. Serial No. 438,095.

To all whom it may concern:

Be it known that I, GEORGE H. SARGENT, a citizen of the United States, residing at Chicago, in the county of Cook and State of Illinois, have invented certain new and useful Improvements in Car-Replacers, of which the following is a specification.

My invention concerns derailed car replacers or rerailers which are employed temporarily as rails or supports for the wheels, the latter rolling up the same and being delivered to and replaced upon the railroad rails. In devices of this character it is essential that they shall possess adequate strength, be simple in design, be effective and efficient in operation, and be of a minimum weight, whereby a single man may readily carry a pair of them without difficulty or discomfort. It is furthermore advantageous to have the construction such that the derailed wheels will travel on their treads on the replacers rather than on their flanges, which, because of the considerable weight or load imposed upon them, have a tendency to cut into or score and break the rerailers. In addition, it is the aim of my present invention to so construct the replacers or rerailers that they will be capable of reversal as regards position alongside the rail, and may consequently be used to rerail a car when rolled upon them from either of two opposite directions.

As will be apparent from the detailed description hereinafter, my improved rerailers belong to the class of derailed car replacers of the single pick-up end wedge-shaped type, rather than to the style or class of rerailers of the straddle-rail or V-shaped pattern.

My improved replacer, which is used to rerail the wheel derailed or displaced outside of the pair of railroad rails, has an inclined or wedge-shaped pick-up or receiving end adapted to be placed under the tread of the wheel, and up which the tread of the wheel is adapted to be rolled. At the delivery or higher end of the replacer, this inclined elevating track merges into or terminates in a broadened discharge terminal portion whose top face is transversely convex, its highest points or line being disposed substantially longitudinally centrally of the replacer. Only that half of the beveled or inclined convex surface of the delivery or dis-

charge end of the replacer adjacent to the railroad rail is employed for sliding or delivering the elevated wheel to the track, the other or opposite half being used when the position of the replacer is reversed alongside the rail to replace a wheel when rolled upon it in the opposite direction. The companion replacer employed to rerail the wheel temporarily derailed between the rails has a receiving and elevating inclined track portion on which the tread of the wheel rolls as described above, but in this replacer the top face of the broadened discharge end is transversely concave and symmetrically disposed in relation to the central longitudinal plane of the device. In this case the discharge end of the structure picks up the flange of the wheel, which by co-operation with the inclined half of the concave face remote from the rail causes the wheel to travel toward and be replaced upon the rail. The concave surface of the one replacer and the convex surface of the other coact with the wheels to effectively and quickly put the derailed truck on the rails. Owing to the symmetrical arrangement and structure of the pair of companion replacers, they may be so positioned along the sides of the railroad rails as to replace a truck when rolled upon them from either direction, it being understood that each replacer has but a single elevating or pick-up end, which is placed under the treads of the wheels.

On the accompanying drawing forming a part of this specification, and to which reference will be made in connection with the following description, I have illustrated a pair of co-operating or companion car replacers or rerailers of preferred and desirable form, and on the various views of the drawing, like reference characters refer to the same parts throughout.

On the drawing,—Figure 1 is a vertical cross-section through the railroad rails illustrating in end elevation the two companion replacers and a portion of a car truck; Fig. 2 is a side elevation of the replacer adapted to rerail the wheel which has been displaced outside of the railroad rails; Fig. 3 is a plan view of the structure shown in Fig. 2; Fig. 4 is an elevation of the left-hand end of the structure shown in Fig. 2; Fig. 5 is an end elevation of the opposite end of the same de-

vice; Fig. 6 is a side elevation of the other replacer; Fig. 7 is a plan view of the same; Fig. 8 is an elevation of the left-hand end of the rerailer shown in Fig. 6, and in addition shows a portion of a car-wheel thereon; Fig. 9 is an elevation of the opposite end of the device shown in Fig. 6; Fig. 10 is a section on line 10—10 of Fig. 6; and Fig. 11 is a section on line 11—11 of Fig. 6.

10 Referring first to the car replacer or rerailer shown in Figs. 2, 3, 4 and 5, it will be noticed that the device is supplied with a wedge-shaped or inclined track 12 substantially I-shape in cross section, the lower 15 tapered end of this elevating track being intended and adapted to be placed under the tread of the wheel derailed outside of the railroad rails. In order to securely maintain this end of the rerailer in place on the 20 cross ties, the base of the same is supplied with a pair of oppositely-extended apertured ears 13, through the holes of which spikes may be temporarily driven into the cross tie. The other or broadened delivery end 14 25 of the device is of shell or box shape construction, being equipped on its base or bottom edge with a plurality of oppositely-inclined spurs or prongs 15 adapted to be pressed into the top face of a cross tie to assist 30 in maintaining the wheel replacer in proper position. This delivery or discharge end 14 of the device is transversely convex, as is clearly indicated in Figs. 1, 4 and 5, the convex surface being symmetrically arranged 35 with respect to the central longitudinal plane of the structure, so that the highest point or line of this discharge end constitutes an extension or prolongation of the wheel elevating track 12, which at its 40 inner end merges into the convex surface, as is clearly shown in Fig. 3.

Giving attention now to the companion rerailer of different construction, shown in Figs. 6 to 11, inclusive, it will be noted 45 that this rerailer has an inclined tread track 16 of substantially I-shape in cross section, and of the same general construction and for the same purpose as the corresponding track 12 of the other wheel replacer. The 50 track 16 is also supplied with apertured ears 17 intended to accommodate and receive spikes to be driven into a cross tie. The other end of this rerailer is of shell construction, as is clearly indicated in Fig. 11, 55 and is equipped along its bottom edge with a number of oppositely inclined or disposed spurs 18 adapted to become pressed into the wood of the cross ties or sleepers. This discharge or delivery end 19 of the replacer 60 is downwardly inclined toward the adjacent end of the device, so as to assist in the rolling and delivery of the wheels on to the rails. This discharge end 19 is broadened at 20 at its inner portion, and is tapered toward the

end of the structure, as indicated in Fig. 7. 65 Its top surface, which is transversely concave and symmetrically disposed with relation to the central longitudinal plane of the device, is somewhat lower in position than the upper end of the elevating track 16, so 70 that as the tread of the wheel leaves the track and passes from the end thereof, the concave surface 19 will receive the flange of the wheel, as is shown in Fig. 8.

The operation of these replacers is substantially as follows: Assuming that both of them have been laid alongside the respective railroad rails with their pick-up or inclined track ends placed beneath the treads of the pair of derailed wheels, the latter are rolled 80 up the tracks 12 and 16, and caused to travel upon the discharge or delivery ends 14 and 19. The flange of the wheel which has traveled up at one side of the track 16 rides upon and engages the inclined half of the concave 85 face 19 remote from the adjacent rail, the tendency of this wheel riding on such a surface being to travel toward the rail and toward the center or lowest portion of the surface 19. Owing to this action of this 90 wheel, the wheel on the convex discharge end 14 of this replacer is drawn to one side of the replacer, as is indicated in Fig. 1, and then has a decided tendency to slide down that part of the convex surface adjacent to 95 the rail transversely of the replacer, this action of this wheel assisting in giving the whole truck a sidewise travel, so as to deliver both wheels on to their respective rails. The contact of the flange of the outside wheel 100 with the tapered portion of its replacer between the track 12 and the broad discharge end also gives to the wheel a sidewise travel toward its rail. It should be noted that the discharge end 14 of the device illustrated in 105 Figs. 1 and 2 is of sufficient height so as to carry the flange of the wheel traveling thereon over the rail, this relation of the parts being indicated in Fig. 1. Since it is not necessary to lift the flange of the other wheel 110 over its rail, it need not be raised as high.

To those skilled in this art it will be apparent that by carrying the wheels on the replacers on their treads for a considerable portion of their travel, I am enabled to make 115 the pick-up ends of the replacers of comparatively light weight and of girder or I-beam construction. The delivery ends of the devices, however, especially the end 19, which carries the full weight on the flange 120 of the wheel, have to be made somewhat stronger, and therefore I employ a shell or box like construction. The two replacers are of comparatively light weight, and are easily carried by a single man. If it is desired to 125 roll the wheels on to the tracks from the opposite direction, this can be readily accomplished by merely reversing the replacers

end for end, in which case the opposite sides of the convex and concave discharge or delivery faces would be employed for giving the sidewise tendency of travel to the wheels 5 to land them on the tracks.

These devices are susceptible of considerable structural change without departure from the substance of my invention, which is not limited to the exact and precise structural features shown and described.

I claim:

1. A pair of coöperating inner and outer railway car replacers the latter composed solely of a base, an inclined track on said base 15 up which the tread of a derailed wheel is adapted to roll, said track terminating in a discharge end having a top transversely-convex face, whereby either inclined side of said convex face may be employed to deliver the 20 wheel to the rail, substantially as described.

2. A pair of coöperating inner and outer railway car replacers the latter being composed solely of a base, an inclined track on said base up which the tread of a derailed 25 wheel is adapted to roll, said track terminating in a discharge end having a top transversely-convex face disposed substantially symmetrically with respect to the longitudinal central plane of the device, where- 30 by either inclined side of said convex face may be employed to deliver the wheel to the rail, substantially as described.

3. A pair of coöperating inner and outer railway car replacers, the latter being 35 adapted to be laid beside the rail and having an inclined track of I-section up which the tread of a derailed wheel is adapted to roll, said track terminating in a discharge end of shell or box section, said end having a top 40 transversely-convex face disposed substantially symmetrically with respect to the central longitudinal plane of the device, where- 45 by either inclined side of said convex face may be employed to deliver the wheel to the rail.

4. A pair of coöperating inner and outer railway car replacers, the former being adapted to be laid beside the rail and having a centrally disposed inclined track up which 50 the tread of a derailed wheel is adapted to roll, said track terminating in a discharge end having a top transversely-concave face, whereby either inclined side of said concave face may be employed to deliver the wheel 55 to the rail, substantially as described.

5. A pair of coöperating inner and outer railway car replacers, the former being adapted to be laid beside the rail and having a centrally disposed inclined track up which 60 the tread of a derailed wheel is adapted to roll, said track terminating in a discharge end having a top transversely-concave face substantially symmetrically disposed with relation to the longitudinal central plane of the

device, whereby either inclined side of said 65 concave face may be employed to deliver the wheel to the rail.

6. A pair of coöperating inner and outer railway car replacers, the former being adapted to be laid beside the rail and having 70 an inclined track of substantially I-section up which the tread of a derailed wheel is adapted to roll, said track terminating in a discharge end of shell or box section having a top transversely-concave face, whereby 75 either inclined side of said concave face may be employed to deliver the wheel to the rail.

7. A pair of railway car replacers adapted to be laid alongside the railroad rails and coöperating to replace a derailed truck or 80 car on said rails, one of said replacers having an inclined track up which the tread of a derailed wheel is adapted to roll, said track terminating in a discharge end having a top transversely-convex face either inclined side 85 of which may be employed to deliver the wheel to the rail, the other replacer having an inclined track up which the tread of a derailed wheel is adapted to roll, said latter track terminating in a discharge end having 90 a top transversely-concave face either inclined side of which may be employed to deliver the wheel to the rail.

8. A pair of railway car replacers adapted to be laid alongside the railroad rails and 95 coöperating to rerail a derailed truck or car, one of said replacers having an inclined track up which the tread of a derailed wheel is adapted to roll, said track terminating in a discharge end having a top transversely- 100 convex face disposed substantially symmetrically with relation to the longitudinal central plane of the device, whereby either inclined side of said convex face may be employed to deliver the wheel to the rail, the 105 other replacer having an inclined track up which the tread of a derailed wheel is adapted to roll, said track terminating in a discharge end having a top transversely-concave face disposed substantially symmetrically 110 with respect to the central longitudinal plane of the device, whereby either inclined side of said concave face may be employed to deliver the wheel to the rail.

9. A pair of railway car replacers adapted to be laid alongside the railroad rails and coöperating to rerail a derailed truck or car, one of said replacers having an inclined track of substantially I-section up which the tread of a derailed wheel is adapted to 115 travel, said track terminating in a widened discharge end of shell or box section having a top transversely-convex face disposed substantially symmetrically with respect to the central longitudinal plane of the device, 120 whereby either inclined side of said convex face may be employed to deliver the wheel to the rail, the other replacer having an in- 125

clined track of substantially I-section up
which the tread of a derailed wheel is adapt-
ed to travel, said track terminating in a dis-
charge end of shell or box section having a
5 top transversely-concave face disposed sub-
stantially symmetrically with respect to the
central longitudinal plane of the device,

whereby either inclined side of said convex
face may be employed to deliver the wheel
to the rail.

GEORGE H. SARGENT.
